(57) **CLAIM**

The ornamental design for a drawer organizer, as shown and described.

DESCRIPTION

FIG. 1 is a top, front, right-side perspective view of a drawer organizer.

FIG. 2 is a front elevational view of the drawer organizer of FIG. 1.

FIG. 3 is a rear elevational view of the drawer organizer of FIG. 1.

FIG. 4 is a right-side elevational view of the drawer organizer of FIG. 1.

FIG. 5 is a left-side elevational view of the drawer organizer of FIG. 1.

FIG. 6 is a top plan view of the drawer organizer of FIG. 1; and,

FIG. 7 is a bottom plan view of the drawer organizer of FIG. 1.

The broken lines in the drawings illustrate portions of the drawer organizer that form no part of the claim.

1 Claim, 6 Drawing Sheets
